UNITED STATES PATENT OFFICE.

AMBER R. CONNER, OF MEREDITH CENTER, AND ALBION A. VEASEY, OF BRISTOL, NEW HAMPSHIRE.

MILK-BOTTLE RECEPTACLE.

1,053,942.

Specification of Letters Patent. Patented Feb. 18, 1913.

Application filed June 6, 1912. Serial No. 702,128.

To all whom it may concern:

Be it known that we, AMBER R. CONNER and ALBION A. VEASEY, citizens of the United States, residing, respectively, at 5 Meredith Center, Belknap county, and Bristol, in the county of Grafton, State of New Hampshire, have invented certain new and useful Improvements in Milk-Bottle Receptacles, of which the following is a specification.

Our invention relates to receptacles for holding milk bottles and the like, and has for its object the provision of a closed receptacle provided with a door and a locking mechanism for said door by which the door may be opened the first time after the lock is set to permit removal of the empty milk bottles and the reception of the filled bottles and after the door is closed the second time, the lock is automatically operated by the closing of the door to securely fasten the door in a closed position to prevent it being opened except by the use of a key.

Our invention will be described in detail hereinafter and illustrated in the accompanying drawings, in which,

Figure 1 is a view in perspective of the box showing it secured to a door post; Fig. 2, a sectional view of the box showing the lock in position after opening the door without the key; Fig. 3, a similar view showing the door locked after having once been open; Fig. 4, a longitudinal sectional view of the box showing the lock in its first position, when set so that the door may be opened without the key; Fig. 5, a sectional view of the door locking mechanism; Fig. 6, a perspective view of the sliding detent; and Fig. 7, a cross section of the cam and the key operating mechanism; Fig. 8, a fragmental top plan view; Fig. 9, a detail view of the cam engaging lever; and Fig. 10, a detail view of the bracket secured to the door.

In the drawings, similar reference characters will be used to designate corresponding parts through the several views.

Our improved milk receptacle 1 is shown secured to a door post A and has mounted on the front side thereof a swinging door 2 admitting to the interior of the box.

Secured to the inner side of the door 2 is a lock casing 3 having slidably mounted

therein a locking bolt 4 having an upstanding lug 5 thereon that is adapted to engage a shoulder 6 on the interior of the casing 55 to limit the outward movement of the locking bolt 4.

7 indicates a pin secured to the rear side of the shoulder 5 and having its free terminal slidably mounted in a socket 8 in the 60 casing 3, 9 indicating a coiled spring mounted on the pin 7 and engaging the bolt 4 and casing 3 to normally project the locking bolt 4 into a locking position.

10 indicates an integral rearward extension 65 from the locking bolt 4 that is slidably mounted in a socket 11 in the casing 3 and provided with a notch 12 in its under side, the forwardmost wall of the notch 12 being inclined as shown at 13.

14 indicates a lever pivotally secured to the door 2 as shown at 15 and having a pin 16 pivotally mounted in a socket 17 in its upper edge that extends through an opening 18 in the under side of the casing 3 to engage 75 the notch 12 in the rearward extension 10 of the locking bolt 4.

19 indicates a spring having one of its terminals secured in one of the arms of the lever 14 as shown at 20, while its other terminal is secured as shown at 21 in the pin 16, said spring being adapted to hold the lever 14 and the pin 16 normally in a position to engage the notch 12.

22 indicates an upwardly extending projection on the terminal of the lever farthest removed from the spring connection 20 and having its upper end beveled as shown at 23.

Secured to the box 1 adjacent to the door opening is a casing 24 provided with two 90 slots designated 25 and 26.

27 indicates a block slidably mounted in the slot 25 and having an elongated notch 28 in its under side to receive a lug 29 extending upwardly from the lower wall of 95 the slot 25 and its extremity farthest removed from the locking bolt 4 having a beveled portion 30 for the purpose to be hereinafter described.

31 indicates a sliding detent mounted in 100 the slot 26 and held normally in a retracted position from the door 2 by means of a bowed spring 32 secured to the box 1 by means of a suitable fastening 33 and having

- one of its terminals engaging a notch 34 in the lower edge of the detent 31, while its other terminal engages the casing 24.
- 35 indicates a notch in the upper rear extremity of the detent 31 and having its lower wall beveled laterally as shown at 36.
- 37 indicates a disk rotatably mounted on the side of the box 1 and spaced apart from the box by means of a suitable washer 38, 10 said disk having a shoulder 39 formed thereon and a notch 40 adjacent to said shoulder. The periphery of the disk 37 commencing from the notch 40 is formed with a cam surface 41, while the remainder 15 of the periphery of the disk is concentric with the pintle 42 to which said disk is secured and that is revolubly mounted in an opening 43 extending through the washer 38 and the side of the casing 1.
- 20 44 indicates a laterally extending cam on the disk 37 that is formed with inclined surfaces 45 and 46 extending toward and away from the shoulder 39 respectively.
- The terminal of the pintle 42 is formed 25 rectangular in cross section as shown at 47 and said terminal 47 is mounted in a keyhole slot 48 in the casing 49 secured to the outer side of the box 1 and is adapted to receive a suitable key 50 for turning said 30 pintle and with it the disk 37. The pintle 42 is secured to said disk by means of a nut or other suitable fastening 51 and 52 indicates a lateral flange on said pintle that engages the outer side of the box 1 adjacent 35 to the opening 43 therein.
- 53 indicates a spring connecting a pin 54 secured to the inner side of the box 1 and pin 55 mounted on the disk 37, said spring normally tending to rotate said disk.
- 40 56 indicates a lever fulcrumed at 57 on the box 1 and having a downwardly extending projection 58 that engages the notch 40 in the disk 37 and is held normally in engagement with said notch by means of a 45 spring 59 secured to the box 1 by means of a pin 60 and having one terminal engaging the upper edge of the casing 24, while its other terminal engages the under side of said lever. The terminal of said lever 56 50 farthest removed from the projection 58 is reduced as shown at 61 and the upper edge of the lever is provided with a shoulder 62, the upper portion of said lever extending rearwardly of said shoulder 62 being inclined as shown at 63.
- 64 indicates an arm having a longitudinal slot 65 therein to receive a pivot pin 66 extending from a block 67 that is angular in cross section as shown in Fig. 8. The outer 60 side of the arm 64 is formed with a notch 68 on the two sides of the slot 65 having its inner surface formed convex to admit of an oscillating movement of said arm 64 on said pin 66, the head of said pin 66 riding on said 65 convex surface of the notch.

69 indicates a pin extending from one terminal of the arm 64 that is adapted to engage the reduced portion 61 on the lever 56, while its other terminal is provided with a pin 70.

71 indicates a bracket secured to the edge of the door 2 and having an inwardly extending projection 72 provided with a notch 73 in its upper edge, having its outer wall inclined upwardly as shown at 74 and the outer portion of the upper edge of said projection 72 inclined downwardly as shown at 75. 76 indicates a spring secured to said bracket 71 and extending inwardly of the door over the projection 72.

In operation, the lock is set with the parts as shown in Figs. 2 and 4. When in this position, the projection 58 on the lever 56 engages the notch 40 in the disk 37 and holds said disk against the action of spring 53 so that the cam 44 on said disk is in engagement with the end of the block 27 and holds said block in the position shown in Fig. 5 to prevent the lock bolt 4 from entering the slot 25. At the same time, the detent 31 is held in its retracted position by the spring 32 and the lever 14 is in its uppermost position as shown in said Fig. 5, so that the pin 16 engages the notch 12 in the locking bolt 4 to prevent said bolt from moving into a locking position. At this time, the milk bottles have been inserted in the receptacle 1 and the door 2 closed, the disk 37 having been rotated by the key 20 to move it into the position stated, and inclined portion 45 of the cam 44 having operated to move the block 27 to retract the bolt 4 to allow the parts to assume the positions stated. At the same time, the door being closed, the pin 70 on the arm 64 is in engagement with the notch 73 on the bracket 71 and is held in engagement with said notch by means of the spring 76, the pin 69 on the other terminal of said arm 64 engaging the reduced portion 61 on the lever 56, and at this period of the operation of the device, the engagement of said pin 70 with the notch 73 operates as a latch to prevent accidental opening of the door 2. At this period in the operation of the device, it will be apparent that any one can open the door 2, and when said door is open for the removal of the empty milk bottles contained therein, the pin 70 will ride upwardly on the inclined portion 74 at the outer extremity of the notch 73 and by so doing, will oscillate the lever 56 so that its downwardly extending end 58 is released from the notch 40 in the disk 37 and said disk will be released to the operation of the spring 53 and be rotated on the pintle 42. When the disk 37 is rotated as stated, the inclined portion 46 of the cam 44 by engaging the notch 35 in the detent 31 will move said detent outwardly of the casing 24 against the resistance of the spring 130

- 32 and hold it in said outwardly extending position, as shown in Fig. 3. This movement of the disk 37 and cam 44 thereon will also bring the inclined portion 45 of said 5 cam into position so that said inclined portion will be opposite the inclined surface on the block 27 and the cam 44 will be no longer in position to interfere with the retractile movement of the block 27. After inserting 10 the full milk bottles in the receptacle, the door 2 will be closed, and in closing said door the projected end of the detent 31 by engaging the beveled portion 23 of the upwardly extending projection 22 on the lever 15 14 will operate to move the end of said lever downwardly against the resistance of the spring 19 and by such downward movement of the lever, will release the pin 16 from engaging the notch 12 in the rearward extension 20 of the locking bolt 4. When said pin 16 is removed from engagement with the notch 12, it will be apparent that the locking bolt 4 will be moved outwardly by the action of the spring 9 and the end of said 25 locking bolt 4 entering the slot 25 of the casing 24 will hold the door in a locked position. Said locking bolt 4 by moving in the locked position as described, operates to move the block 27 into its rearmost position. 30 To open the door, when locked as just described, the key 50 is inserted in the slot 48 and into engagement with the end 47 of the pintle 42 and the disk 37 rotated by said key against the resistance of the spring 53. 35 When the disk 37 is rotated as stated, the inclined portion 46 of the cam 44 is moved upwardly to permit the spring 32 to withdraw the projecting terminal of the detent 31 into the casing 24 and at the same time 40 the inclined portion 45 of said cam engages the beveled portion 30 of the block 27 to move said block, and with it the locking bolt 4 against the resistance of the spring 9 until the locking bolt assumes the position 45 shown in Fig. 5 when the pin 16 will be moved upwardly into engagement with the notch 12 and the parts will be in the position as first described. 50 Having thus described our invention, what we claim is:—
1. In combination with a receptacle having a swinging door, a locking bolt slidably mounted on said swinging door, means to hold said sliding bolt in a retracted position, a sliding detent mounted in the receptacle and adapted to move said locking bolt holding means from engagement with the locking bolt, and means to reciprocate said detent into and out of engagement with said 55 locking bolt holding means.
2. In combination with a receptacle and a door therefor, a sliding bolt mounted on said door, a lever mounted on the door, a pin pivotally secured to said lever and adapted to engage the locking bolt to hold 60
- it in a retracted position, a detent slidably mounted in the receptacle and adapted in one of its positions to engage said lever and move the pin from engagement with the locking bolt, and means to reciprocate said 70 detent.
3. In combination with a receptacle and a door therefor, a spring actuated sliding bolt mounted on said door and having a notch therein, a spring actuated lever pivotally mounted on the door, a pin pivotally secured to said lever and adapted to engage the notch in the locking bolt, a detent slidably mounted in the receptacle and adapted in one of its positions to engage said lever 75 to move the pin from engagement with the locking bolt, a block also slidably mounted in said receptacle and adapted to engage the locking bolt to retract it against the resistance of said spring, and means to reciprocate said detent and block.
4. In combination with a receptacle and a swinging door therefor, a spring actuated locking bolt slidably mounted on said door and having a notch therein, a spring actuated lever pivotally mounted on said door and having an integral beveled projection, a pin pivotally mounted on said lever and adapted to engage the notch in the locking bolt, a detent slidably mounted in the receptacle and adapted to engage the beveled projection on the lever aforesaid in one of its positions, a block slidably mounted in the receptacle and adapted to engage the locking bolt to retract it against the resistance 90 of said spring, a spring secured to said detent and normally tending to retract it from engagement with the lever aforesaid, a disk revolvably mounted in the receptacle and having a cam adapted to engage said detent 95 to project it against the resistance of said spring and also to engage said block to move it and the locking bolt as aforesaid, means to hold said disk stationary, and means operated by the door to release said 100 holding means.
5. In combination with a receptacle and a swinging door therefor, a spring actuated locking bolt slidably mounted on said door and having a notch therein, means engaging 115 said notch to hold said locking bolt in a retracted position against the resistance of said spring, a block slidably mounted in the receptacle and adapted to engage said locking bolt to retract it, a detent slidably mounted in the receptacle and adapted to engage the locking bolt holding means to release it, a spring engaging said detent and normally tending to hold said detent out of engagement with said locking bolt holding 120 means, a spring actuated disk journaled in said receptacle and having a notch in its periphery, a laterally extending cam on said disk and adapted to engage said block and detent to move them into their operative position.

sitions, said cam operating said block and
detent by alternative movements of said
disk, a lever fulcrumed in said receptacle
and engaging the notch in the disk, an arm
5 pivotally secured in the receptacle and en-
gaging said lever, and means secured to said
door to actuate said arm and move the lever
from engagement with the notch in the disk.

In testimony whereof we affix our signa-
tures in presence of two witnesses.

AMBER R. CONNER.
ALBION A. VEASEY.
